Assignor to.
The Lowell Manufacturing Company,
Letters Patent No 1670. Dated Nov 21, 1862

The schedule referred to in these Letters Patent and making part of the same
To whom it may concern

Be it known that I, Elamir J. Ney, of Lowell, in the County of Middlesex and State of Massachusetts, have originated and designed a new Pattern for Carpets or other fabrics, of which the following is a full, clear and exact description, reference being had to the accompanying drawings, making part of this specification.

The principal features of this design, are series of set figures, of a Persian style, connected by small bands, on each of which rests a small block.

The spaces between the principal figures are occupied by grounds of small regular work.

each supporting a small outline figure,

The colors employed for the different portions of the design may be varied to suit the taste and wish of the manufacturer.

— Claim —

What I claim as my invention and desire to secure by letters patent, is the design or pattern for Carpets, or other fabrics, herein set forth,
